COMBINATION RADIO AND TELEVISION CABINET

Skiro Jordon, Baltimore, Md., assignor of five per cent to Thelma Jordon, five per cent to Robert L. Jordon, and five per cent to Otelia E. Jordon, Baltimore, Md.

Application May 3, 1955, Serial No. 35,796

Term of patent 14 years

(Cl. D56—4)

Figure 1 is a front perspective view of a combination radio and television cabinet showing my new design, with the doors thereof being in closed position; and

Figure 2 is also a front perspective view of the same, with the doors in open position.

I claim:

The ornamental design for a combination radio and television cabinet, as shown.
